UNITED STATES PATENT OFFICE.

CHARLES G. NOBLE AND JAMES T. KING, OF EUGENE, OREGON.

CABLE CAR.

Application filed November 25, 1927. Serial No. 235,647.

The present invention relates to cable cars adapted particularly for use in holding heavy crates or material such as logs or lumber upon inclined surfaces.

5 An object of the invention is to provide a car truck having a plurality of drums rotatably mounted thereon and operated through a power plant carried by the truck, and about which a stationary cable may be 10 arranged with its ends anchored at the opposite end of a railway and adapted through the frictional engagement of the cable with the drum to cause the forward or rearward movement of the car upon the rotation of 15 the drum.

A further object is to provide brake beams for certain of the drums adapted to secure the same against rotation, the frictional engagement between the cable and the drum 20 when idle serving to retain the car against movement.

A further object of the invention is to form a gear wheel integrally with each of the drums and arranged for engagement with 25 each other for simultaneous rotation of the drums, said drums being arranged in a double row along different horizontal planes with the cable carried thereupon, with the respective rows of drums mounted for rotation in opposite direction, whereby through 30 such arrangement to enable the positive frictional engagement between the cable and the drum for operating the car without any lost motion.

35 A still further object is to provide an apparatus of this character of simple and practical construction, strong and durable, efficient and reliable in performance, relatively inexpensive to manufacture and operate and otherwise well adapted for the purposes for which the same is intended.

40 Other objects and advantages reside in the special construction and combination of the various elements comprising the invention, reference being had to the accompanying drawings forming a part hereof, wherein:—

Figure 1 is a top plan view,

Figure 2 is a view in side elevation,

Figure 3 is a vertical transverse sectional 50 view and

Figure 4 is a vertical transverse fragmentary sectional view through one end of the car showing one of the cable guide pulleys arranged at the end thereof.

55 Referring now to the drawings in detail, the invention comprises a car truck compris-

ing a horizontally disposed frame indicated at 5 mounted upon a pair of truck wheels 6 at each end for travelling upon rails 7.

The platform includes a plurality of 60 spaced parallel longitudinally extending frame members 8 disposed intermediate the sides thereof, the upper edge of said frame members forming a support for a plurality of bearing brackets 9 for rotatably mounting 65 shafts 10 extending transversely of the car and upon each of which cable drums 11 are rotatably supported.

The lower edges of the frame members 8 also provide means for attaching a plurality 70 of bearing brackets 12 forming a mounting for a series of lower shafts 13 upon which drums 14 are rotatably carried.

At one side of each of the drums 11 and 14 are formed spur gear wheels 15, the gears 75 of the upper and lower sets of drums being engaged for simultaneous operation with each other. By this arrangement the upper row of drums are disposed for rotation in an opposite direction from the lower row of 80 drums as illustrated by the direction shown in Figure 2 of the drawings. Each of the upper shafts 10 extend toward one side of the car, the intermediate shaft having a relatively enlarged gear 16 keyed for rotation 85 therewith and constituting a drive gear for connection with a power plant of any suitable character mounted on the car and by means of which the various gears and drums 90 may be operated.

The upper shafts 10 at each side of the center shaft are provided with brake drums 17 having brake bands 18 arranged thereabout in braking relation therewith and operatively connected by brake rod 19 which 95 is attached to a brake lever 20 mounted upon a support 21 disposed between the drums 17.

As illustrated in Figure 2, the brake rods 19 extend in opposite directions from the lever 20 and are attached at opposite sides of the pivot 22 of the lever so that the movement of the lever in one direction will operate the rods in opposite direction. In order to enable the brake bands 18 to be applied simultaneously through the operation of the lever 100 in a predetermined direction, the mounting of the brake band on the respective drums 17 is reversed.

The traction for the car is derived through 110 means of a cable 23 having its ends anchored at the opposite end of the tracks 7 and extending between a pair of horizontally dis-

posed guide pulleys 24 mounted at each end of the car and then partially wound alternately about the upper and lower sets of drums. To accomplish the proper winding 5 of the cable about the drums in the manner indicated, the upper and lower sets of drums are provided in an uneven number, the present embodiment of the invention indicating an upper set of drums, three in number, with 10 the lower sets of four of such drums. The cable is first wound partially about the lower end drum, then about the adjacent upper drum and back around the second lower drum and so on throughout the device until each 15 of the drums are partially engaged by the cable in the manner indicated.

It will be apparent that upon winding the cable about the drums in the manner indicated and by creating a suitable tension upon 20 the cable that a positive gripping action will occur between the cable and the drums resulting in the movement of the car in a pre-determined direction upon the operation of the drums.

25 Furthermore upon the stopping of the drive means for the drum and applying the brakes through the lever 20 the friction engagement between the drums and the cable will serve to retain the car in position against 30 movement and thus enable the car to be held against movement even upon severe grades.

Cable cars constructed in accordance with 35 our invention are admirably adapted for use in transporting logs, lumber and other heavy material over grades at a minimum cost of construction, maintenance and operation.

It is obvious that the invention is susceptible 40 of various changes and modifications, without departing from the spirit or scope of the invention or sacrificing any of its advantages, and we accordingly claim all such forms of the device to which we are entitled.

Having thus described our invention, what we claim as new is:

1. In an apparatus of the class described, 45 a vehicle having a plurality of horizontally disposed rows of drums rotatably mounted thereon and operatively connected with each other and the stationary cable wound about each of said drums. 50

2. In an apparatus of the class described, a wheeled vehicle, an upper and lower row of drums rotatably mounted thereon, gears attached to each of said drums and mounted for engagement with each other for simultaneous rotation, the upper row of drums being arranged for rotation in a direction opposite from said lower row of drums, one of said drums having a drive gear connected therewith, braking means operatively engageable with a pair of said upper drums and a stationary cable engaging each of said drums. 55 60

3. In a cable car of the class described, a car platform, car wheels for the same, a plurality of cable drums rotatably mounted upon the upper and lower edges of the platform and disposed in staggered relation with respect to each other, gear wheels formed on each of said drums, the upper gear being arranged for engagement with the lower gear for simultaneous rotation of the drum, said upper and lower drums being disposed for operative rotation, a drive gear connected with one of the upper drums, brake means 75 operatively engageable with a pair of the upper drums, a stationary cable, cable guide pulleys mounted at each end of the car, said cable being arranged about said upper and lower drums in alternate arrangement. 80

In testimony whereof we affix our signatures.

CHARLES G. NOBLE.
JAMES T. KING.
